JOINT FOR CONCRETE SLABS
 Edward D. Garner, 5724 Seward St., Lincoln, Nebr.
 Filed July 16, 1964, Ser. No. 383,175
 5 Claims. (Cl. 94—8)

This invention relates to a joint structure for concrete slabs and more particularly for use in forming the joint between adjacent slabs in the construction of roads, runways and the like.

Various types of joint structures are presently in use in road construction including the use of dowels which is employed with this invention and one of the important objects contemplated herein is the provision of an improved dowel type joint structure that is sturdier and more efficient than those presently in use.

More particularly it is an object of this invention to provide a dowel type joint structure for concrete slabs that is simple and easy to make and install and one which will not break or collapse under the weight of wet concrete as it is poured.

To attain these objects and such further objects as may appear herein, or be hereinafter pointed out, reference is made to the accompanying drawings forming a part hereof, in which:

FIG. 1 is a perspective view showing a concrete slab joint structure embodying this invention,

FIG. 2 is an enlarged transverse section of a joint between two concrete slabs showing my joint structure in operative position, and

FIG. 3 is an enlarged sectional view of one end of one of the dowels showing its supporting structure in relation to the road bed prior to the pouring of the slab.

Referring to the drawings, a road bed or sub-grade is designated by the numeral 10 which is prepared to support the concrete slabs 12 and 14 which have for purpose of a reference the respective top and bottom surfaces 16 and 18. The joint 20 between the slabs 12 and 14 is formed after the concrete has set as will later be referred to.

With reference now more particularly to FIGS. 2 and 3, this joint structure 22 includes a pair of parallel spaced angle iron runners or supports 24, to each of which there are secured, preferably by welding, the longitudinally spaced and oppositely disposed upstanding support rods 26. As best seen in FIG. 3, each rod 26 extends upwardly from runners 24 to point 28 where it is bent towards the opposite like rod 26 to form a supporting shoulder 30 and then extends upwardly to point 32 where it is again bent toward the opposite rod 26 to terminate in the horizontally disposed projection 34. The projections 34 on each pair of opposed rods 26 serve to support a dowel member 36 by nesting in a respective socket or recess 38 provided in each end of each dowel. This arrangement provides a most efficient and sturdy support for the dowels and will not break or collapse as frequently occurs in other forms of joint structure having different dowel supporting means.

Rods 26 are further braced by the respective elongated rods 40 which connect the several rods 26 on each respective runner 24 and which are welded 42 to the top of the respective shoulders 30.

For ease and convenience in handling structure 22 until it is in place, rods 40 are preferably tied together in any suitable manner such as by the wire strands 44. It can thus be easily placed on the road bed 10 where runners 24 are transverse to the longitudinal axis of the road and dowels 36 will be parallel with such axis. Preferably dowels 36 are approximately one foot apart and an entire structure 22 itself may be located approximately every twenty feet of road length although it will be understood that such dimensions may be varied in different circum-

2

stances and under different conditions. It will also be understood that a joint structure 22 as shown is generally used on slabs that represent a half width of the complete roadway.

With a structure 22 placed on the road bed 10 as described, runners 24 are anchored in place by hook members 46 that engage the runners and are driven into bed 10 and in this position, wires 44 may be removed or not as desired. Dowels 36 are also coated with a suitable lubricant as is well known to prevent them from bonding with the concrete and to permit expansion and contraction of the concrete, and in this regard, the supporting structure for the dowels afforded by the projections 34 and recesses 38 eliminates any external contact with the dowel that is present in other forms of joint structures and thereby avoids leaving any dowel areas where there is no lubricant. As a result, the dowels cannot become bonded to the concrete to reduce the effective results intended as frequently occurs with some other type joints.

The concrete is poured over the structure 22 in accordance with known practices and after it has hardened, the joint 20 is formed by a concrete saw from top 16 to the top of the dowels 36 as best seen in FIG. 2. Joint 20 is then filled with felt or tar 50 as is well known.

This joint structure 22 as described requires less material and less welding and fabrication than other joint structures for the same purpose and the novel supporting means for the dowels 36 as indicated has demonstrated its superiority and greater efficiency for its intended purpose over structures presently in general use. Thus, from the foregoing, it is thought a full understanding of the construction and operation of this invention will be had and the advantages of the same will be appreciated.

It will be understood that the phraseology employed herein is for the purpose of description and not for limitation and that modifications and changes in the construction and arrangement of this invention can be made within the scope of what is claimed, without departing from the spirit and purpose thereof. It is thus intended to cover by the claims, any modified forms of structure or mechanical equivalents which may be reasonably included within their scope.

I claim:

1. In a joint structure for adjacent concrete slabs, the combination of:
 a pair of spaced parallel runners,
 a plurality of upstanding support rods secured to and spaced longitudinally on each runner,
 each rod terminating at its top in a horizontal projection extending toward but not to the other runner and each rod on each runner being oppositely disposed to a respective rod on the other runner,
 a plurality of dowels each provided with a recess in each end,
 each dowel supported by a respective pair of support rods by having one of said projections nested in each recess, and
 temporary tie means between opposed rods for maintaining the terminal ends of opposed rod supports seated in said recesses.
2. A device as defined in claim 1 including:
 means anchoring each runner to a roadbed whereby said runners are rendered immobile and correspondingly maintain the terminal ends of opposed rod supports seated in said recess so that said temporary tie means can selectively be removed or retained in place.
3. A device as defined in claim 2 wherein said runners are angular in cross section to prevent them from turning on their axes.
4. A joint structure for use in the pouring of adjacent

concrete slabs on a roadbed, said structure comprising:
 a pair of spaced runners adapted to be placed on the roadbed transversely of the longitudinal axis of a concrete slab to be poured,
 a plurality of spaced dowels each provided with an end socket on each end and adapted to be imbedded in and to extend parallel to the longitudinal axis of the concrete slab when it is poured,
 opposed rod support means on said runners having terminal ends seated in said sockets to support said dowels within said slab when it is poured so that the entire external surface of said dowels is free of contact with said terminal ends and in contact with the slab material,
 temporary tie means between opposed rods for maintaining the terminal ends of opposed rod supports seated in said sockets, and
 means anchoring each runner to the roadbed whereby said runners are rendered immobile and correspondingly maintain the terminal ends of opposed rod supports seated in said recess so that said temporary tie means can selectively be removed or retained in place.

5. A device as defined in claim 4 wherein said runners are angular in cross section to prevent them from turning on their axes.
